US00D723364S

(12) **United States Design Patent**
Halbur et al.

(10) **Patent No.:** US D723,364 S
(45) **Date of Patent:** ** Mar. 3, 2015

(54) **TOY CONTAINER**

(71) Applicant: **Target Brands, Inc.**, Minneapolis, MN (US)

(72) Inventors: **Ted C. Halbur**, Lino Lakes, MN (US); **David Ledsinger**, Golden Valley, MN (US); **Jared P. Kreuzer**, Minneapolis, MN (US); **Maggie Harn**, Minneapolis, MN (US); **Stacy Abel**, Maple Grove, MN (US); **Donald C. Clark**, Seattle, WA (US)

(73) Assignee: **Target Brands, Inc.**, Minneapolis, MN (US)

(**) Term: **14 Years**

(21) Appl. No.: **29/496,707**

(22) Filed: **Jul. 16, 2014**

(57) **CLAIM**

The ornamental design for a toy container, as shown and described.

DESCRIPTION

FIG. 1 is a front, perspective view of a toy container showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

In the drawings, the broken lines depict unclaimed subject matter only and form no part of the claimed design.

1 Claim, 4 Drawing Sheets
